ELECTRIC HEATER

James L. Smith, Murfreesboro, Tenn., assignor to Edwin L. Wiegand Company, Pittsburgh, Pa.

Filed May 15, 1967, Ser. No. 7,118

Term of patent 14 years

(Cl. D81—10)

FIG. 1.

FIG. 2.

FIG. 3.

FIGURE 1 is an elevational view of one side of an electric heater showing new design, the opposite side being a substantial mirror image thereof, and

FIGURES 2 and 3 are top and end views, respectively, of the heater.

I claim:

The ornamental design for an electric heater, substantially as shown and described.
